UNITED STATES PATENT OFFICE

SARAH M. GILLARD, OF HUNTINGTON, WEST VIRGINIA

KITCHEN SINK

Application filed May 1, 1929. Serial No. 359,633.

This invention relates to sinks, for use in kitchens, restaurants, etc., of the type which includes strainers, and other convenient receptacles.

5 An object of the invention is to provide a sink with a number of conveniences generally found useful while working at said sink.

10 A further object is to locate said conveniences where they will be readily accessible and easily manipulated, without needless extra effort, and without a change of position.

In the accompanying drawings—

15 Fig. 1 represents a front view of the sink;

Fig. 2 represents a plan view of the same;

Fig. 3 is a view, partly broken away, of a detail;

20 Fig. 4 is a view of a vertical longitudinal section of a part of the sink, on the line 4—4 of Fig. 2;

Fig. 5 is a view of a horizontal longitudinal section on the line 5—5 of the part 25 shown in Fig. 4;

Fig. 6 is a view of a vertical section on the line 6—6 of Fig. 2;

Fig. 7 is a horizontal section of the part 30 shown in Fig. 6, on the line 7—7 of Fig. 1;

Fig. 8 is a top view of the cover over the garbage receptacle shown in Figs. 6 and 7.

In Fig. 1, the sink 1 is provided with the customary back board 2, supporting the 35 faucets 3, 4, and the swinging soap basket 5. To the right is shown a valve handle 6, which controls a supply of hot water in the rinsing bowl, referred to later. At the front of said sink is a wall section 35, Fig. 1, 40 in the left side of which is a section 7, containing a drawer 8, (see Figs. 4 and 5) which drawer is divided into suitable compartments 9, 10. The top of section 7 serves as a drain board, or table, to support soiled 45 dishes, etc. Within the drawer 8 may be placed tea towels, or other supplies. The "wash basin" 11, below the soap basket, see Figs. 1, 2, 4, and 5, is preferably provided with a suitable stopper 12, (Fig. 4) which 50 permits it to be filled with water when de-

sired. The soap basket 5 may be swung under the hot water faucet 3 to provide soapy water, the basket 5, serving to hold small pieces of soap. The drain pipe 13, Fig. 4, is connected to the sewer in the usual manner.

To the right of the basin 11 is a section 14 containing compartments 15 and 16, Figs. 6 and 7; in compartment 15 is a removable wire basket 17 which serves as a garbage receptacle, the compartment 15 being provided with a drain pipe connection 18; the compartment 16 serves as a receptacle for such scouring materials as steel wool, soap, etc. The section 14 is covered with a tilting cover 19, Figs. 6 and 8, the cover being actuated by the movement of the knob 20 which moves in the slot 21, Figs. 1 and 3, and is connected to the tilting cover 19 by the cable 22 and bell-crank 23, see Fig. 3, 70 or by other equivalent devices; the cable travelling over pulleys 24, 24. The knob 20 is so positioned that it may be operated by a side movement of the hip of a person standing in front of the basin 11, thereby 75 raising the cover 19, the weight of the cover being sufficient to drop the same and close the compartments 15 and 16 upon the release of the knob 20.

To the right of the section 14 is the rinsing bowl 25, which is connected by outlet 26 and pipe 27 to the drain 13, Fig. 4. Within the rinsing bowl 25 is the spray pipe 28, and spray head 29, which are connected through valve 6 to a supply of hot 80 water. After dishes, etc., have been washed, they may be placed in the bowl 25, and sprayed with hot water from the spray head 29. The bowl 25 is covered with a dished, or pan-shaped cover, 30, provided 85 with a handle 31, Figs. 1 and 2, containing an enlarged loop 32, and when desired, the cover 30 may be inverted and placed upon the cover of the section 14 with the loop 32 90 engaging the spray head 29, see Fig. 6, and exposing the rinsing bowl 25, the pan-shaped cover may then be used to dry the sprayed 95 cover taken from the rinsing bowl, or for other purposes. The entire sink may be supported on the legs 33, 33, Fig. 1.

The sink illustrated may be regarded as a "right-handed" sink. The several sections may however, extend toward the left, thereby making a "left-handed" sink, without departing from the invention. It will be noted that all of the several sections are placed side by side, affording a pleasing appearance, with the sections conveniently located so as to be readily accessible to a person without leaving the position in front of the wash basin.

I claim—

In a kitchen sink with a depending front wall section, a vessel in said sink behind said wall section, a tilting cover for said vessel, said cover having a bell-crank lever projecting downwardly behind said wall section, pulleys below the surface of said cover behind said section, a horizontal slot through said front wall section, a horizontally movable knob slidable in said slot, a cable connecting said bell-crank and said knob and passing over said pulleys, whereby the sliding of said knob in said slot serves to raise said cover, and said cover adapted to close upon the release of said knob.

In testimony whereof I hereby affix my signature.

SARAH M. GILLARD.
